JAMES R. BAKER, OF ARLINGTON, NEW JERSEY, ASSIGNOR TO COOPER HEWITT ELECTRIC CO., OF HOBOKEN, NEW JERSEY, A CORPORATION OF NEW JERSEY.

MERCURY-VAPOR APPARATUS.

1,091,180.

Specification of Letters Patent. Patented Mar. 24, 1914.

Application filed April 10, 1912. Serial No. 689,802.

To all whom it may concern:

Be it known that I, JAMES R. BAKER, a citizen of the United States, and resident of Arlington, county of Hudson, State of New Jersey, have invented certain new and useful Improvements in Mercury-Vapor Apparatus, of which the following is a specification.

One broad method widely used in commercial work for starting mercury vapor apparatus is the use of a starting band on high potential. This is normally very satisfactory but in certain cases, notably in a very clean or a very cold lamp, an inconveniently high potential is required. This applies also to alternating current lamps where the initial storage of energy in the choke coils is not quite as easy on account of the high impedance of these coils to the initial alternating current. It was found some time ago that if the surface of the inside of the glass at the level of the cathode were altered in such a way as to change the meniscus of the mercury, so as to make it more nearly flat and less round, the starting was much easier. This, for example, was accomplished in the Recklinghausen Patent No. 750,891, dated February 2nd, 1904, by the burning in of platinum on the inside of the glass. Other expedients have been, for example, the use of titanium nitrid instead of platinum. In the present invention applicant makes use of a different material, namely, carborundum, to serve this purpose.

In the practical embodiment of the apparatus, convenient-sized crystals of carborundum, preferably powdered, are made to adhere to the surface of the glass and somewhat beyond the surface of the cathode, and this is found to affect the meniscus in the desired manner and will facilitate the starting of the lamp to quite a marked degree. It is sometimes of advantage to construct this lamp in such a way that the current will come in contact with the carborundum before the lamp is sealed from the pump. This material is of further advantage in that it avoids a difficulty that has been found with other methods of obtaining the same general result. If the mercury wets the material used on the inside of the glass too freely, the current has a tendency to settle at the point of contact between the mercury and the substance, in which case the material is vaporized and thrown off into

the lamp, causing a blackening of other parts of the container and also in some cases removing material from the point where it is required for starting purposes. This difficulty has been avoided by locating the adherent material at a point not naturally visited by the normal running current. Such an arrangement is shown in application Serial Number 453,186, filed September 15th, 1908. With carborundum, however, the action is extremely advantageous, for the normal operating current does not settle at the surface of the carborundum nor is there any tendency for this material to be thrown into the vapor space. The carborundum may thus be located in any convenient location.

One convenient method of causing adherence between the carborundum and the glass is by spreading the crushed carborundum on the surface of the glass and heating the glass to the softening point, after which the particles of the carborundum will remain fixed in position.

It is not necessary that the carborundum form a circuit around the entire surface of the cathode but it may cover a very small portion, though a few millimeters will be sufficient. In practice, however, I prefer to use a somewhat longer exposure of the appropriate surface.

I have illustrated my invention in the accompanying drawings in which—

Figure 1 is a vertical section of a gas or vapor electric lamp of the character described; and Fig. 2 is a plan view thereof, partly in section.

In the drawings I have shown such a lamp consisting of a tube or container, 1, provided at one end with a positive electrode, 2, of iron, a cathode, 3, of mercury, or other suitable liquid, at the opposite end, said electrodes being connected to a suitable source of current (not shown) by means of leading-in-conductors, 4 and 5. The usual starting band located on the outside of the tube in proximity to the cathode is shown at 6 and is connected by a wire 7, with the leading-in conductor 4, of the positive electrode 2. A coating of carborundum here appearing as a short strip is shown at 8, attached to the inside wall of the container in the neighborhood of the cathode and extending slightly beyond the edge thereof.

The desired altered condition of the

meniscus of the cathode due to its impinging on the jagged surface of the carborundum strip, is shown at 9.

It is known that apparatus constructed on the principle of the Cooper Hewitt lamp may be utilized for other purposes than that of illumination, while at the same time such apparatus is subject in a general way to the same laws as the lamp itself. For example, it may require starting devices, and accordingly my present invention is applicable not only to gas or vapor electric lamps, but broadly to apparatus of this character whether used as a lamp or not.

I claim as my invention:

1. An electrode for vapor electric apparatus consisting of a quantity of mercury and a body of non-metallic granular material wetted thereby penetrating the meniscus of the mercury.

2. An electrode for vapor electric apparatus consisting of a quantity of mercury and a body of non-metallic granular material dividing the meniscus of the mercury at its edge.

3. An electrode for vapor electric apparatus consisting of a quantity of mercury and a body of non-metallic granular material interrupting the normal continuity of the mercury meniscus.

4. An electrode for vapor electric apparatus consisting of a quantity of mercury and a body of non-metallic granular material interrupting at its edge the normal continuity of the mercury meniscus.

5. An electrode for vapor electric apparatus consisting of a quantity of mercury and a body of non-metallic granular material wetted thereby dividing the meniscus of the mercury.

6. An electrode for vapor electric apparatus consisting of a quantity of mercury and a body of non-metallic granular material wetted thereby dividing the meniscus of the mercury into sections.

7. An electrode for vapor electric apparatus consisting of a quantity of mercury and a body of non-metallic granular material wetted thereby dividing the meniscus of the mercury into sections at its edge. 50

8. An electrode for vapor electric apparatus consisting of a quantity of mercury and a body of carborundum penetrating the meniscus of the mercury.

9. An electrode for vapor electric apparatus consisting of a quantity of mercury and a body of carborundum dividing the meniscus of the mercury at its edge. 55

10. An electrode for vapor electric apparatus consisting of a quantity of mercury and a body of carborundum dividing the meniscus of the mercury at its edge into sections. 60

11. In a vapor electric apparatus, a starting material therein consisting of a body of carborundum in contact with the negative electrode of the apparatus. 65

12. In a gas or vapor electric apparatus, a starting material consisting of a body of carborundum attached to the container and in contact with the negative electrode of the apparatus. 70

13. In a gas or vapor electric apparatus, a starting material consisting of a body of carborundum in contact with and projecting beyond the edge of the negative electrode of the apparatus. 75

14. In a gas or vapor electric apparatus, a starting material therein consisting of a body of carborundum attached to the container and in contact with and projecting beyond the edge of the negative electrode of the apparatus. 80

Signed at New York in the county of New York and State of New York this 8th day of April A. D. 1912.

JAMES R. BAKER.
